C. J. MAY

JAR HOLDER

Filed Dec. 17, 1925

Inventor
Charles J. May

By Clarence O'Brien

Attorney

UNITED STATES PATENT OFFICE.

CHARLES J. MAY, OF MISHAWAKA, INDIANA.

JAR HOLDER.

Application filed December 17, 1925. Serial No. 75,989.

This invention relates to jar holders, and has for its primary object to provide a relatively novel, but efficient form of tool wherein fruit jars, cans, and the like may be rigidly held against turning movement while the usual closure cap is being applied to or removed therefrom.

A further object is to substantially improve upon and simplify tools of this general nature, and in the attainment of this end I have constructed such a jar holder that consists of but two essential members that may be readily connected, or disconnected for usage or storage purposes respectively.

With the above and other objects in view, as the nature of the invention will be better understood, the same comprises the novel construction of jar holder hereinafter more fully described, shown in the accompanying drawing and claimed.

In the drawing wherein like reference characters indicate corresponding parts throughout both the views,

Figure 1 is a top plan view of my improved holder, and

Figure 2 is a side elevation thereof.

Now having particular reference to the drawing, my novel holder constitutes the provision of a pair of relatively wide V-shaped metallic jaws 5 and 6, the opposite sides of which extend outwardly in relatively great converging relation in order that jars A of various diameters may be disposed and held therebetween, the inner surfaces of the jaws being provided with compressible linings 7-7 in order that a proper grip will be secured between the jaws and the jar held thereby.

Certain ends of the jaws are detachably connected through the medium of a curved

hook 8 being formed at said end of one of the jaws for detachable engagement through a slot 8' at the similar end of the other jaw, this connection permitting of a pivotal movement of the jaws with respect to each other. 45

The opposite ends of the jaws are formed with horizontally extending handles 9-9 that are curved outwardly transversely, as shown, throughout their length, in order to permit of a comfortable grip in the squeezing 50 of the jaws 5 and 6 around the jar A.

It will thus be seen that great pressure may be provided upon the jar for preventing any slippage of the same while the cap is being applied to or removed therefrom. It 55 will also be seen that jars of various diameters may be rigidly held by the present holder and that the jaw members may be readily connected or disconnected for a purpose above mentioned.

Having thus described the invention, what I claim as new and desire to secure by Letters Patent is:—

In a jar holder of the class described a pair of relatively wide V-shaped metallic 65 jaw members between which a jar may be disposed, anti-slipping lining secured upon the inner faces of said jaws, means at one end of the jaws whereby the same may be detachably pivoted together, said means comprising a hook formed on one jaw member and adapted for engagement within a slot formed within the end of the other jaw member, the other ends of the jaw terminating in horizontally extending handles, said 70 handles being curved transversely throughout their length.

In testimony whereof I affix my signature.

CHARLES J. MAY.
